METHOD OF FORMING DITCH LININGS

Willis Leriche, Allentown, Pa., and Ira V. Beasley,
Yukon, Okla., assignors to Cement Gun Com-
pany, a company of Delaware

Application July 14, 1931. Serial No. 550,726

5 Claims. (Cl. 61—14)

This invention relates to means for and a method of lining ditches and more particularly to the formation of the upper edges of linings for ditches where the ditches are carefully shaped 5 in the dirt and a lining of "Gunite" or the like is applied directly against the dirt.

An important use of the invention is in connection with irrigation ditches. For many years these ditches were used without linings. With 10 this arrangement there was considerable waste of water and it was difficult to keep the ditches clear. More recently it has been the practice to line the ditches with "Gunite" or the like which can be applied very readily and of which a thin reinforced layer is sufficient to give the requisite 15 strength. A great advantage of this kind of lining is that it can be applied without the use of forms and therefore economically.

In this connection, it may be said that "Gunite" 20 may be formed by forcing sand and cement in proper proportions and under suitable air pressure from a "cement-gun" through a suitable hose to a nozzle where the mixture is hydrated. The material is driven from a nozzle in a stream 25 and at high velocity against a suitable base or back. Under these conditions the material is pneumatically tamped to form a dense mass constituting "Gunite".

In the construction of ditches of the class referred to, it is found to be particularly desirable 30 to form the ditch with its cross section substantially in the form of a segment of a circle. This form accommodates a maximum flow and gives great strength with a very thin lining. The 35 lining may be reinforced by suitable means such as a metal mesh or fabric which is stretched along the ditch and secured in place in properly spaced relation with reference to the inner surface of the ditch. Then the "Gunite" is blown 40 into place against the dirt as backing and the mesh completely covered. Ordinarily the lining is about one inch thick and the ditch is from two and one-half to three feet in radius.

However, in shaping the inner surfaces of these 45 ditches the upper edges are frequently broken away as a result of loose dirt failing to remain in position or to irregular breaking away at the surface of the ground particularly where the dirt is of the type from which adobe is made and has 50 been hardened by drying. Under such conditions it is necessary, in order to get the inner surfaces of the upper edges of the lining at the desired position, to increase the thickness of the lining at 55 those parts. This decreases very much the spread of a given amount of material and correspondingly increases the cost of lining ditches and particularly so in that such ditches are usually of very considerable length.

An important object of the invention is to provide means for readily avoiding such disadvan-

tages. Another important object is to provide a method for obtaining the same general results.

In carrying out the present invention, use may be made of removable top edge forms which may be secured in position so as to provide a suitably positioned backing for the upper edges of the lining. These forms may also be provided at their upper edges with means, such as inwardly extending flanges, to gauge the thickness of the lining at its upper edge and also to determine the 65 position of the edge surfaces of the lining.

Other features and advantages will appear upon consideration of the following description and of the drawing in which

Fig. 1 is a view in cross section of a ditch 75 provided with a lining formed in accordance with the present invention;

Fig. 2 is a longitudinal vertical section;

Fig. 3 is a fragmentary view on a larger scale 80 of a top form of the type illustrated in Fig. 1;

Fig. 4 is a sectional view corresponding to one side of Fig. 1 but showing a modified top edge form; and

Fig. 5 is a view illustrating the top edge form shown in Fig. 4 when not in use in a ditch. 85

Referring to the drawing, 10 designates a ditch of which the cross section may be in the form of a circular segment. The inner surface 11 of the ditch proper is formed as accurately as possible in the dirt or earth and is provided with a 90 suitable lining 12 of "Gunite" or the like suitably reinforced as by means of metal mesh or fabric 13 having longitudinal members 14 and transverse members 15.

In forming the lining the mesh or fabric is 95 stretched along the ditch and is positioned at the proper distance from the shaped dirt surface by suitable means such as spacing device 16 which is used where required. Although no great difficulty is encountered in obtaining and 100 maintaining the desired shaping of the greater part of the dirt surface forming the backing of the "Gunite" lining, it is found impossible from a practical standpoint to obtain the proper shaping at the top edges of the ditch due, for example, 105 to the slipping down of loose dirt or earth and the breaking away of hardened material in chunks.

This condition as to the edges of the ditch is 110 illustrated in Figs. 1 and 4 in which the inner dirt surface 11 is shown as having portions 17 sloping from the desired position of the dirt surface. Consequently when the "Gunite" was blown into place, it was necessary to make the lining at these parts considerably thicker than in the main part of the ditch in order to get the inner 115 surfaces of the corresponding parts of the lining in the proper positions. These linings are not very thick (one inch, for example) and the excess of material at the edges reduces considerably the spread of the material. Formerly it 120

was also the practice to support gauging strips for the top edges of the lining or stakes driven into the earth. Then after the "Gunite" was blown in around the stakes, they were removed leaving holes which were filled later with "Gunite".

According to the present invention, various difficulties including those referred to may be avoided by the use of suitable top edge forms or shooting-strips of which one kind 18 is shown in Figs. 1, 2 and 3. This strip or form 18 may include a part of flange 19 intended to engage at one edge the dirt at the lower edge of a portion 17 of the dirt surface. At its upper edge the part or flange 19 is provided with another flange 20 which, when the strip or form is in Fig. 1 position serves as a gauge for the extreme edge of the "Gunite" lining 12.

The flange 19, which extends downwardly may for all practical purposes be flat inasmuch as it is of small width (four inches, for example,) when compared with the radius of the ditch. Each strip 18 may be of sheet metal and may be reinforced by a member 21 (of wood, for example,) and the strip may be supported by pins 22 passing through openings 23 in the member 21. These pins may be driven into supports 24, such as wooden stakes driven into the earth, or may be driven directly into the earth. When stakes 24 are used, the wooden strips or members 21 may, by engagement with the stakes hold the shooting strips firmly in position against the pressure of the "Gunite" when blown thereagainst. After the "Gunite" lining has been applied, the top edge strips or forms 18 and stakes 24 may be removed. Ordinarily the vacant spaces between the "Gunite" lining 12 and the portion 17 of the inner surface of the excavation will gradually fill up with dirt.

In Figs. 4 and 5 there is illustrated another embodiment 18a of the shooting strip or forms. In this case the reinforcing strip for the upper flange 20a is omitted and both flanges 19a and 20a are made of metal of sufficient strength to give the necessary stiffness. The strips or forms 18a may be supported by pins 22a passing through eyes 25 at the upper side of the flange 20a. As shown in Figs. 4 and 5, the flange 20a is provided at its upper side with lugs or projections having suitable openings and constituting the eyes 25. The openings of the eyes are inclined with reference to the upper flange 20a so that the pins enter the earth at a greater depth and firmly hold the shooting strip or form more firmly in position.

It should be understood that various changes may be made in the means and method of the present invention and that certain features may be used without others without departing from the true scope and spirit of the invention.

Having thus described our invention, we claim:

1. A method of lining a ditch shaped in the dirt to the predetermined cross section except at the top where dirt is broken away, comprising stretching mesh material along said ditch to conform substantially with the shape thereof, applying removable forms of substantially uniform size at the upper edges of the ditch with the inner faces of said forms at the desired position for the outer surface of the lining, securing the forms in position by means attached to the forms and having engagement with the ground, and applying cementitious material to cover the mesh and form a lining of substantially uniform thickness.

2. A method of lining a ditch shaped in dirt to the predetermined cross section except at the top

where dirt is broken away, in connection with the use of forms each including a substantially flat portion with a thin lower edge and attaching devices at the upper edges, said method comprising stretching mesh material along the ditch to conform substantially with the shape thereof except at the broken away portions, applying the removable forms with their lower edges engaging the dirt at the lower edges of the broken away portions and with their inner faces at the desired position for the outer surface of the lining, supporting the forms and maintaining the spacing of the upper edges thereof from the sides of the ditch by use of said attaching devices, and applying cementitious material to cover the mesh and form a lining of suitable thickness.

3. A method of lining a ditch shaped in dirt to the predetermined cross section except at the top where dirt is broken away, in connection with the use of forms each including a substantially flat portion with a thin lower edge and an upper inwardly extending flange provided with eyes whose axes are substantially perpendicular to said flat portion, said method comprising stretching mesh material along the ditch to conform substantially with the shape thereof except at the broken away portions, applying the removable forms with their lower edges engaging the dirt at the lower edges of the broken away portion and with their inner faces at the desired position for the outer surface of the lining, supporting the forms and maintaining the spacing of the upper edges thereof from the sides of the ditch by pins passing through said eyes, blowing hydrated cementitious material into position to cover the reinforcing material, and removing the forms.

4. A method of lining a ditch shaped in dirt to the predetermined cross section except at the top where dirt is broken away, in connection with the use of forms each including a substantially flat portion with a thin lower edge and an upper inwardly extending gauge portion provided with eyes whose axes are substantially perpendicular to said flat portion, said method comprising stretching mesh material along the ditch to conform substantially with the shape thereof except at the broken away portions, applying the removable forms with their lower edges engaging the dirt at the lower edges of the broken away portion and with their inner faces at the desired position for the outer surface of the lining, supporting the forms and maintaining the spacing of the upper edges thereof from the sides of the ditch by pins passing through said eyes and into the dirt, and applying cementitious material to cover the mesh and form a lining of suitable thickness.

5. A method of lining a ditch shaped in dirt to the predetermined cross section except at the top where dirt is broken away, in connection with the use of forms each including a substantially flat portion having a thin lower edge and attaching means adjacent to its upper edge, said method comprising applying to the ditch mesh material stretched along the ditch in conformity with the shape thereof except at the broken away portions and said removable forms so as to engage the dirt at the lower part of the broken away portions and to be held by use of said attaching means spaced from the sides of the ditch with their inner faces at the desired position for the outer surface of the lining, and applying cementitious material to cover the mesh and form a lining of suitable thickness.

WILLIS LERICHE.

IRA V. BEASLEY.
